Primary Examiner — Selina Sikder(74) *Attorney, Agent, or Firm* — John M. Hammond;
Patent Innovations LLC(57) **CLAIM**

The ornamental design for a display panel, as shown and described.

DESCRIPTION

FIG. 1 is a perspective view of the top, front and left side of the display panel;

FIG. 2 is a front elevation view of the display panel;

FIG. 3 is a right side elevation view of the display panel;

FIG. 4 is a rear elevation view of the display panel;

FIG. 5 is a left side elevation view of the display panel;

FIG. 6 is a top plan view of the display panel; and,

FIG. 7 is a bottom view of the display panel looking upwardly from below.

Any broken line illustration of environmental structure in the drawings is for illustrative purposes only, and forms no part of the claimed design.
